BALE-TIE BUCKLE

Ezra A. Frantz, Weatherford, Tex.

Application June 21, 1933, Serial No. 676,960

2 Claims. (Cl. 24—26)

My invention relates to bale tie buckles, and more particularly to a one-piece buckle for tying cotton bales and the like; and the object is to provide a bale-tie buckle which is simple in structure, durable, and positive in operation. Another object is to provide a buckle which is adapted to hold the cooperating ends of the cotton bale bands so that the bands will have uniform tension about the cotton bale.

10 A still further object is to provide a bale buckle especially adapted for use on what are commonly called high density bales. When used on high density bales, the buckle is subjected to great strain and the present invention seeks to provide 15 a buckle which will have a maximum strength, notwithstanding the fact that it is formed from a minimum quantity of stock.

An advantage of this invention is that the cross-sectional contour of the body of the buckle 20 insures correct curvature of the cooperating ends of the bale bands, thus eliminating the danger of the bands slipping. Another advantage of this invention is that provision is made in the one-piece buckle to lock the buckle in operative position for holding the bands. Another advantage of this buckle is that the locking means operates 25 automatically when the bale bands are expanded against the buckles. Other objects and advantages will be fully explained in the description 30 and the invention will be more particularly pointed out in the claims.

Reference is had to the accompanying drawing which forms a part of this application.

Figure 1 is a face view of the buckle and the 35 cooperating ends of the cotton bale bands;

Fig. 2 is a similar view, showing the buckle in locked position;

Fig. 3 is an end view of the buckle in normal position;

40 Fig. 4 is a similar view, showing the buckle in locked position;

Figs. 5, 6 and 7 constitute a series of views illustrating the locking action of the buckle.

45 Figs. 8, 9, 10 and 11 illustrate different cross-sections of material adapted for carrying out the present invention.

Similar characters of reference are used to indicate the same parts throughout the several views.

50 The device consists of a bar of suitable material which is bent to form a loop, or buckle body, which is approximately rectangular. The ends of the one-piece rectangular form are overlapped to provide a locking means or means to 55 keep the buckle from being pulled out of shape

when the bale bands are expanded. The ends 1 of the bale band are looped over the upper side 2 of the form and the lower side 3 of the buckle, so that when the bands are placed under tension, the pull is against the long sides 2, 3, of the rectangular formed buckle.

More specifically, the buckle may be described as having a top member or bar 2 and a lower bar 3, which are normally approximately parallel with each other, and side members 4 and 5. One end of the band is looped over the upper member 2 and the other end of said band is looped around the lower member 3. The end member 4, which is an extension of the upper bar 2, is formed to extend over the end of the lower bar 3 to form a 60 retainer or lock for the member 3 when it is expanded or moved to operative position under the influence of the tension under which the band is placed. This arrangement provides a locking 65 means for the buckle or a means for holding the 70 normal shape of the buckle against displacement by the tension of the bale band.

In the edge view, Fig. 3, the side or end 4 of the buckle is formed to extend downwardly from the upper bar 2 and forward so that it passes in front

80 of the end of the bar 3, at which point it is bent to extend around the bar 3, adjacent the end 6 thereof, to form the locking means. The end 4 of the buckle is extended forward of the true vertical plane to form a throat whereby the looped 85 end of the band can be placed over the lower bar 3. The retaining element or hook 7 of the end 4 is formed to provide a V-shaped recess for receiving the bar 3 when the tension of the bands tends to expand the bars 2 and 3 or tends to 90 pull the two apart. The V-shaped form is provided by bending the end 4 around and under the bar 3. The bottom of the V is normally a fraction of an inch forward the vertical plane of the buckle so that when the bar 3 is pulled downward, it will first strike the inner slope of the V of the hook 7, adjacent the cotton bale as shown at B in Fig. 6. Further pull of the bar 3, by the 95 tension of the band 1, will cause the bar 3 to slide down the inner slope of the V and into the bottom of the V of the hook 7, as illustrated in Fig. 7. This form of buckle provides a support for the lower bar which automatically acts to brace itself against being pulled out of shape.

When ends of a band are looped around the bars 2 and 3, the tension of the bands tends to pull the two bars away from each other. As they expand under the influence of the tension of the bale band, bar 3 rides upon the slope of the V, and the free end of the hook is forced into the cotton 105 110

bale by the movement of the buckle to permit the end of the member 2 to come to rest in its locked position or into the bottom of the V of the hook 7. Forcing the end of the hook 7 into the cotton bale acts to support the V of the hook against being bent out of shape by the movement of the bar 3.

In order to increase the strength of the buckle and to more securely retain the looped ends of the bale band, the present buckle is made of a length of stock of non-circular cross-section. Preferably, the stock is of rectangular cross-section, but other irregular shapes such as illustrated in Figs. 8 to 11, may be used. As shown in Figs. 15 to 5, when material of angular cross-section is used, the angles or corners are made somewhat rounded. The curvature should not be formed on too large a radius as the sharper the curve the greater the bite it will take in the bale band. On the other hand, the curvature must not be on too small a radius because if the bend formed in the band at the corner of the metal is too acute, shearing or rupture of the band will result. In other words, those corners, or edges, of the stock which engage the band must be abrupt or acute enough to bite into the band and permanently distort the fibers of the band material, so as to securely hold the tensioned band against slipping or creeping but, at the same time, said corners must not be too acute as to shear the tensioned band. In forming up the buckle, the stock is bent to shape so that one of the edges will form the inner periphery of the buckle and an edge or corner of the stock will form the outer extremity 30 of the buckle. By forming the buckle in this manner, the lower edge of the bar 3 is positioned, normally, to fit into the bottom of the V of the hook when the buckle is pulled into locked position, as shown in Fig. 4 and at C in Fig. 7. The 40 edges of the round cornered square stock provides three points of contact with the inner periphery of the loop of the band 1, as shown at D in Fig. 8, which insures a positive hold of the band.

It is apparent that the cross-sectional contour of the stock which the buckle may be bent from may vary, as shown in Figs. 8 to 11, but it has been found that an angular or oval form more readily adapts itself to forming the correct loop in the ends of the bale band and will more readily 50 position itself in the locking recess 7 of the buckle. When the buckle is made of square material and bent upon an edge of the square the buckle will have more rigidity and will form a more secure hold for the loops of the bands.

55 In addition to the fact that stock of non-circular cross-section will function more efficiently to hold the band ends against slipping, non-circular stock is also highly advantageous in that

it materially increases the capacity of the buckle to withstand strains imposed on the buckle by the tensioned bands. This is of considerable importance when the buckle is used on high density bales. In other words, if the same quantity of metal in a piece of stock of circular cross-section is embodied in a piece of stock of non-circular cross-section, and the latter is formed into a buckle as shown in the present case, the major cross-sectional dimension of the stock is disposed in the plane in which the tension strains of the bale band are imposed on the buckle. As a consequence, the buckle will withstand greater loads. This is quite apparent from inspection of both the rectangular and oval stock. In the latter instance, if the stock was circular and had a uniform curvature corresponding to the curvature of the so-called biting edges, the buckle would not stand up under the strains normally imposed upon it. However, with the oval cross-section, the necessary strength is obtained.

What I claim is:

1. A bale-tie buckle composed of a bar of bendable material having a major and a minor cross-sectional dimension, said bar being bent into a buckle having oppositely disposed members around which the ends of a bale band may be looped with the major cross-sectional dimension of said bar disposed in the plane of tensional strains imposed on said members by the bale band, and one end of said bar constituting an extension of one of said members and having a hook formed therein in which the other of said members is received, the major cross-sectional dimension of that portion of the bar constituting said hook also being disposed in said plane in which tensional strains are placed on said members.

2. A bale-tie buckle for cotton bale bands and the like formed up from a bar of metal, said buckle comprising upper and lower members adapted to receive the looped ends of the band, one end of said bar being extended from one of said members to form a V-shaped hook extending around the other member for retaining said buckle in shape when tensional strains are imposed on the band and buckle, one side of said V-shaped hook portion being positioned to one side of the plane in which said strains are imposed on the buckle, and the inclined surface of the other side of said hook portion being positioned in alignment with the side member of the buckle adapted to be retained in said hook, said inclined surface when engaged by said side member being adapted to effect a lateral movement of the hook and end of the bar to the opposite side of the plane in which tensional strains are imposed on the buckle.
